MUSICAL INSTRUMENT

Charles P. Kimmel, Gary, Ind.

Application March 23, 1942, Serial No. 435,812

18 Claims. (Cl. 84—404)

My invention relates to musical instruments, and particularly to an instrument in the nature of a pedal piano or pedalier.

An object of my invention is to provide means associated with a dancing platform by which the dancer may play his own musical accompaniment, or supplement an accompaniment provided by other means. Novel features of my invention comprise improvements in the form and arrangement of the action, and in the arrangement of the pedal keys that are intended for operation by the feet of the dancer. The construction is such that it adapts itself for a compact foot operated instrument having a relatively wide range; that is to say, the instrument may provide for as many as eighty-eight notes within a relatively small space.

One of the important considerations in the construction of an instrument of the type of the present invention is that of providing for suitable multiplication of movement between the pedal and the striking hammer, it being desirable that the movement of the pedal key shall be relatively small if quick action such as required for rapidly repeated notes is desired. Since the force available for the actuation of the keys is relatively great as compared to that normally exerted by the fingers, a construction may be adopted in which the necessary pedal movement is comparatively minute. Furthermore, provision should be made for insuring against damage to the action in the event that an unexpectedly great force is exerted on a key.

As stated, an important feature is that of the arrangement of the keys relative to the tones that may be produced. Since an operator has but two feet, as compared with ten fingers available for playing a conventional piano, I have so arranged the keys that harmonies may be produced by the use of either or both feet.

While the invention, in certain of its aspects, is particularly concerned with an instrument adapted for pedal operation, it is to be understood that other aspects of the invention, such for example as the form and arrangement of the action are adapted for use with percussion type instruments generally, including conventional pianos and the like.

The advantages and possibilities of arrangement of the invention will be apparent from the following description.

Fig. 1 is a plan view of a combined dancing platform and musical instrument constructed in accordance with the principles of the invention; and

Fig. 2 is a sectional view of the instrument on the line 2—2 of Fig. 1.

In the drawings a supporting frame is indicated by the numeral 10, transverse members 11, 11a, 11b, et cetera, serving to support the various elements of the assembly.

A dancing platform is made up of horizontal flat sections 12 supported at one end on one of the frame members 11 and at the opposite end 10 on a frame member 13. These sections cover a free or open space, as will be best understood by reference to Fig. 2. The remainder of the platform is made up of rectangular sections 14 supported at their sides on the frame members 13 and containing oval, elongated openings for receiving the foot pedals or keys 15. Firmly secured within the openings are cylinders 17 open at top and bottom. The stems 18 of the keys 15 are vertically reciprocable within and guided 20 by the cylinders 17. Bearing plugs 19 are secured within the lower ends of the key stems, the key stems also being provided at their lower ends with flanges 19a adapted to be brought into abutting engagement against the lower ends of the cylinders 17 to limit the upward movement of the keys. The downward movement of the keys is limited by the seating of the key heads within their seats 15a, formed in the sections 14.

It will be noted that each key 15 is seated with 30 in the recess in the section 14 so that it is substantially flush with the general surface of the platform, and that but very slight clearance is provided beneath the key and the seat 15a provided in the section 14. Thus the movement necessary to seat the key is very slight—in practice about $\frac{1}{2}$ of an inch.

A link 20, adjustable as to length by means of an adjustment screw 20a, is provided for each key, for connecting the lower end of the key stem 40 to a lever 21 pivoted as indicated at 23 on a frame bracket 24. The link is provided with spherical heads on either end thereof for engaging the plug 19 and a seat formed on the end of the lever 21. Lever 21 is provided with an arm 22 connected by means of a link 25 with the short end 26 of a bell-crank, pivoted at 27 to the bracket. The long arm 28 of the bell-crank is connected to a pull rod or tracker 29 that extends longitudinally of the structure and is connected with the juncture of the two arms 31—32 of a toggle, the lower end of toggle link 31 being pivotally mounted on a bracket 33 carried by a subframe member 11a. A flexure spring 30 is also mounted on the bracket 33, this flexure spring being bifurcated at its upper end so as to loosely embrace

the pull rod 29. The rod is provided with an abutment surface 29a which is adapted to engage the spring at a predetermined point as the rod is shifted to the left as seen in Fig. 2, upon depression of its actuating key 15.

A link or push rod 34 connects the upper link 32 of the toggle to a rocker 35 pivoted at 36 to a bracket carried by a frame cross piece 11b. A guide link 32a pivotally mounted upon the bracket 33, pivotally connects with the toggle link 32 and the link 34, to insure the proper movement of the link 34 as the toggle is operated.

A link 37 is connected at its lower end to the rocker 35, and at its upper end has a wide head 37a engageable with the counterweight 38 formed as a part of the striking hammer. The striking hammer is pivoted at 43 to a bracket secured to the cross piece 11b, the pivot point being such as will substantially balance the hammer. Extending oppositely from the counterweight 38, the hammer is provided with an extending arm or shaft 41, the end 41a of which carries the hammer head 39 which is adapted to strike the tone producing element 40 when the hammer is operated. This tone producing element may be a wire or bar, or other suitable tone element. The two shaft portions 41 and 41a of the hammer are connected for slight relative pivotal movement by a flexure spring 42, for a purpose later to be described. The flexure spring normally maintains the shaft portions 41 and 41a in the position illustrated in Fig. 2, a felt pad or the like 42a being provided for limiting the action of the spring. A compression spring 44 normally holds the hammer in its raised position, as shown in Fig. 2.

The wide head 37a of the link 37 provides two contact points 45-46 that engage with corresponding contact surfaces formed on the hammer counterweight 38, the point 45 being a substantial distance removed from the pivot point 43 of the hammer; and the point 46 being removed a lesser distance. When the parts are in normal position as shown in Fig. 2, before depression of the operating key 15, the head is in contact with the counterweight at the point 45, there being a slight space between the parts at the point 46, as shown in Fig. 2. Thus upon operation of the key resulting in an upward thrust of the link 37, the initial upward thrust upon the counterweight 38 will be at the point 45, a point substantially removed from the pivot of a hammer, facilitating the overcoming of the hammer inertia. Immediately thereafter, however, the contact is at the point 46 which is close to the pivot 43; thus increasing the velocity of the hammer.

The rocker 35 has at its end an operating bar 47 which is adapted to engage a bell-crank 48 carrying a damper 49. The bell-crank 48 is pivotally mounted upon a bracket secured to the cross frame 11b, the damper 49 being adjustably mounted on the end of the bell-crank, by means of an adjustment nut 49a. The parts are so arranged that as the rocker 35 is moved to operate the striking hammer 38, the bell-crank 48 is simultaneously operated to lift the damper 49.

Means is provided for limiting the pivotal movements of the striking hammer, such means taking the form of adjustable abutments engageable with the counterweight 38 for limiting its movement. More specifically, a cross frame member 11c carries an abutment member 50 ad-

justably mounted on the cross frame by means of an adjustment screw or the like 51. The abutment member 50 is provided with a pad 52 of felt or other suitable material, the pad being adapted to be engaged by the counterweight 38 to limit the clockwise or striking movement of the hammer. Similarly, an abutment member 53 is pivotally mounted on a bracket secured to the cross frame 11c, this abutment member being provided with a pad 54 on its lower end for limiting the counterclockwise shifting of the counterweight. An adjustment screw 55 is provided for adjustably positioning the abutment member 53.

In operation, as the operating key 15 is depressed, the pull rod or tracker 29 will be shifted to the left as seen in Fig. 2, effecting a straightening of the toggle 31, 32, and an upward shifting of the push link 34. This in turn results in a clockwise shifting of the rocker 35 and an upward movement of the push link 37. As the link 37 is operated the striking hammer is shifted clockwise about its pivot 43. The abutment member 50 is so adjusted that it arrests the movement of the counterweight 38 when the hammer striking head 39 reaches a position slightly spaced from the tone element 40, for example a suitable fraction of an inch or the like. The flexure spring 42 thereupon permits inertia of the hammer head 39 to complete the striking movement of the head into engagement with the tone producing element. After the head has engaged the element, the flexure spring immediately operates to return the head to its slightly raised position and separate the parts. Simultaneously as the striking hammer is operated by the push link 37, the damper 49 is raised by the bell-crank 48, as previously pointed out. As the operating force upon the key 15 is released, the springs 44 and 30 operate to restore the parts to normal position. The spring 30, by its engagement with the tracker abutment portion 29a, operates to effect an immediate breaking of the toggle; and the compression spring 44 operates to restore the striking hammer to its normal raised position as shown in Fig. 2. The counterclockwise shifting of the striking hammer, into normal raised position, is limited by the engagement of the counterweight against the adjustable stop member 53.

An important feature of the action is the contact arrangement 45-46 between the push link 37 and the hammer counterweight 38. As previously pointed out, the arrangement is such that as the link 37 is initially raised to operate the hammer, the point of engagement 45 which is relatively widely spaced from the hammer pivot point 43, furnishes a relatively great mechanical advantage to overcome the inertia of the hammer counterweight and associated parts. Thereafter, after movement of the hammer has been initiated, the point of engagement 46 becomes operative. This point of engagement furnishes a lower mechanical advantage, a high mechanical advantage being no longer needed. However, the contact point 46 furnishes a higher speed ratio to insure adequate and rapid movement of the hammer as the key is depressed.

A further important feature of the construction is the action of the flexure spring 42, together with the adjustable abutments 50 and 53 for the hammer counterweight. The abutment 50 may be adjusted to impart a proper arresting motion to the counterweight, permitting the flexure spring to effect a proper striking action between the hammer head 39 and the tone produc-

ing element 40, the action being neither too heavy nor too light under the desired operating conditions.

The toggle 31, 32 is so arranged that as it is initially moved by the tracker 29, a maximum rate of movement is imparted to the push link 34 and parts operated thereby. Continued movement of the toggle, as it approaches its straight line position, results in a lesser rate of movement of the link 34. In this connection the action of the return spring 30 should be noted. It will be seen that this return spring, which is engaged at a predetermined position in the movement of the tracker 29, operates immediately upon release of the key 15, to break the toggle from its straight line position. Accordingly, even though the link 34 has its slower rate of travel when the toggle approaches its straight line position, the restoring spring 30 insures a quick-acting return of the parts.

The adjustment screw 20a of the link 20 also provides ready adjustment means for insuring proper operation of the action as the key 15 is depressed. This adjustment screw may be operated to effect an accurate adjustment between the key and the operated lever 21, to insure the proper force and movement of the striking action, with each individual key.

Where space is to be conserved and a relatively large number of notes are to be provided for, I provide alternate series of actions and tone producing elements in staggered and superposed relation, as shown in Fig. 2. As the upper and lower actions are similar, no further specific description will be made. It will be understood, however, that longitudinally adjacent pedal keys will be connected alternately to upper and lower actions, as best shown in Fig. 2. Thus the key shown at the left in Fig. 2 has its tracker 29' connected by means of a toggle to a link or push rod 34' long enough to extend upwardly beyond, but in line with the link 34.

It will be understood, of course, that the actions in the upper and lower series will be staggered relative to each other, so that the lateral spacing of the actions will be equal to the lateral spacing of diagonally adjacent keys, as shown in Fig. 1. In Fig. 1 no effort has been made in the broken out arrangement to illustrate both upper and lower series of actions, only the lower series being shown.

As a means for throwing all of the actions out of operation, I provide lock-out control keys 57 and 58 mounted at opposite ends of a rocker 59, Fig. 2, connected to a push rod 60 having a spring detent 60a cooperating therewith. The lower end of the rod 60 is connected to a bell-crank 61 which, through a link 62, is adapted to operate one of a series of bell-cranks 63, fixed to a shaft 64. As best shown in Fig. 1, there is one bell-crank 63 for each rocker 35. Upon depression of the key 58, the bell-cranks 63 are operated to raise the rockers 35, thereby lowering the associated hammers and holding them out of operative position. Depression of the key 57 restores the parts to the operative position of Fig. 2, the detent 60a being provided for maintaining the rocker 59 in the position to which it is moved, either by the actuation of the key 58 or the key 57. The bell-cranks 63 are further provided with push rods 65 engageable with the rockers 35' for the upper series of actions, for the same purpose as the bell-cranks 63 are engageable with the rockers 35 of the lower series.

It should be understood that while the tone producing elements 40 have been shown in horizontal position, they may be arranged vertically with a corresponding change in the position of the actions. Also, many of the features of the action may be found to be of value in other forms of musical instruments, particularly of the percussion type.

The matter of key arrangement is important and is subject to variation in many respects. In Fig. 1 I have indicated certain tones by the appropriate designations on the spaces adjacent to the keys. At the upper half of the drawing I have shown a platform section wherein the notes are arranged chromatically, additionally providing that the laterally adjacent keys as indicated at 15a and 15b, are arranged in fifths. At the lower half of the figure I have shown a keyboard section having an arrangement by which the longitudinally adjacent keys 15c and 15d are arranged in thirds, and this is likewise true of the keys 15c and 15e in lateral juxtaposition. In this arrangement the diagonally adjacent keys 15c and 15f are arranged in fifths. This illustrates the facility with which numerous arrangements may be provided. Another arrangement in a simplified construction may be one in which alternate rows of keys are arranged according to the diatonic scale and disposed in thirds or fifths.

With arrangements such as described a dancer may produce harmonic tones with either or both feet, and two dancers may produce a full set of harmonics.

Obviously the arrangements may be varied within wide limits, and modifications may be made in the apparatus shown; and I do not wish to be limited except as indicated in the appended claims.

40 The invention is hereby claimed as follows:
1. In a pedal piano, the combination of a series of pedal keys arranged in longitudinally and laterally spaced relation, a tone element for each key, an action for each key including a hammer, and means connecting each key to its action, said connecting means lying in juxtaposed laterally spaced relation and the longitudinally adjacent keys being offset laterally to at least the extent of the lateral width of the said connecting means.

45 2. In a pedal piano, the combination of a series of pedal keys laterally aligned and longitudinally offset, a series of tone elements, and actions connecting the keys and tone elements, said tone elements and actions being in juxtaposed laterally spaced relation and being laterally spaced apart to the extent of the lateral offset of the keys.

50 3. In a pedal piano, the combination of a series of pedal keys laterally aligned and longitudinally offset, two series of tone elements, one arranged above the other in staggered relation, and connecting actions between the tone elements and keys, longitudinally adjacent keys being connected to alternate upper and lower tone elements.

55 4. In combination, a platform adapted for dancing, a series of pedal keys substantially flush with the surface of said platform, tone elements and actions arranged in a bank in juxtaposed laterally spaced relation, connections including trackers connecting the actions to the keys, and means in said actions and connections for multiplying the motion of the keys relative to the strikers of the actions.

5. In combination, a platform adapted for dancing, a series of pedal keys substantially flush with the surface of said platform, tone elements and actions, connections including trackers connecting the actions to the keys, and means in said actions and connections for multiplying the motion of the keys relative to the strikers of the actions, said keys being arranged in longitudinally staggered relation whereby to provide straight tracker connections to closely spaced tone elements.

6. In combination, a platform adapted for dancing, a series of pedal keys substantially flush with the surface of said platform, tone elements and actions, and means connecting the actions to the keys, said keys being in diagonally disposed relation and being so spaced that two thereof may be simultaneously actuated by one foot of an operator.

7. In combination, a platform adapted for dancing, a series of pedal keys sunk in and substantially flush with the surface of said platform, tone elements and actions, and means connecting the actions to the keys, said keys being in diagonally disposed relation and being so spaced that two thereof may be simultaneously actuated by one foot of an operator, certain tone elements in thirds being connected to adjacent keys that are so spaced.

8. In combination, a platform adapted for dancing, a series of pedal keys sunk in and substantially flush with the surface of said platform, tone elements and actions, and means connecting the actions to the keys, said keys being in diagonally disposed relation and being so spaced that two thereof may be simultaneously actuated by one foot of an operator, certain tone elements in fifths being connected to adjacent keys that are so spaced.

9. In combination, a platform adapted for dancing, a series of pedal keys substantially flush with the surface of said platform, tone elements and actions, and means connecting the actions to the keys, said keys being in diagonally disposed relation and being so spaced that two thereof may be simultaneously actuated by one foot of an operator, tone elements in harmonic relation being connected to adjacent keys that are so spaced.

10. In an action for a musical instrument, the combination of a tone producing element, a hammer engageable with said element, a thrust bar for moving the hammer, a toggle for moving the thrust bar, a tracker for exerting a pull tending to straighten the toggle, a shiftable key, and means for transmitting the thrust of the key to a pull on the tracker.

11. In an action for a musical instrument, the combination of a tone producing element, a hammer engageable with said element, a thrust bar for moving the hammer, a toggle for moving the thrust bar, a tracker for exerting a pull tending to straighten the toggle, a key arranged for vertically downward straight line movement, and means for transmitting the thrust of the key to a pull on the tracker.

12. In an action, the combination of a tone

producing element, a pivoted hammer having a striker engageable with the element on operation of the hammer, a thrust member engageable with the hammer on the side of the pivot opposite to the striker for operating the hammer, means for operating the thrust member, said thrust member having a wide head, one point on which contacts the hammer when in normal position at a point removed from the pivot, and another point on the head for contacting the hammer at a point nearer to the pivot, as the thrust member is operated and the hammer moves toward striking position.

13. In an action, the combination of a tone producing element, a hammer comprising a striker engageable with the element on operation of the hammer, a pivot for the hammer, said hammer having a counterweight outside of the pivot, and a push rod having a head provided with laterally separated contact faces adapted on operation to successively engage surfaces on the counterweight to actuate the hammer, the faces engaging surfaces nearer to the hammer pivot point as the hammer moves to striking position, and means for operating the push rod.

14. In an action, the combination of a key, a tone producing element, a hammer having a striker engageable with said tone producing element on operation of the hammer, and an action connecting the key and the hammer whereby operation of the key operates the hammer, said hammer being formed of an operating portion and a striking portion, said two hammer portions being resiliently connected by resilient spring connecting means, and means for limiting the operating movement of the hammer operating portion.

15. In combination, a platform adapted for dancing, a series of pedal keys sunk in and substantially flush with the surface of said platform, tone elements and actions, trackers connecting the actions to the keys, and a single means for rendering all said keys inoperative.

16. An action for a musical instrument as defined in claim 10, wherein adjustment means is provided for adjusting the position of the key with respect to the position of the toggle.

17. An action for a musical instrument as defined in claim 10, wherein spring means is provided for breaking the toggle upon release of the key.

18. In an action, the combination of a tone producing element, a pivoted hammer having a striker engageable with the element on operation of the hammer, a thrust member engageable with the hammer in predetermined spaced relation to the pivot thereof for operating the hammer, means for operating the thrust member, said thrust member having a wide head, one point on which contacts the hammer when in normal position at a point removed from the pivot, and another point on the head for contacting the hammer at a point nearer to the pivot, as the thrust member is operated and the hammer moves toward striking position.

CHARLES P. KIMMEL.
